INSULATOR-SUPPORTING FIXTURE.

1,149,282.

Specification of Letters Patent. Patented Aug. 10, 1915.

Application filed May 4, 1914. Serial No. 836,115.

To all whom it may concern:

Be it known that I, CHARLES L. PEIRCE, Jr., a citizen of the United States and a resident of Pittsburgh, in the county of Allegheny and State of Pennsylvania, have invented certain new and useful Improvements in Insulator-Supporting Fixtures, of which the following is a specification.

My invention relates to insulator supporting fixtures and involves improved construction.

The purpose of the invention is to provide a strong, inexpensive fixture particularly adaptable for supporting the conductors of high tension circuits and which can be readily secured in place, as for example on a pole, with a minimum of labor and expense and without the need of gaining the pole.

More in detail, the invention contemplates the construction of fixtures of pipe lengths rigidly secured together by strong and durable castings which are curved to accurately fit the surface of the supporting pole.

The various features of the invention are clearly shown on the accompanying drawing in which—

Figure 1 is an elevational view of one of my improved fixtures and one end of the pole to which the fixture is secured, and Fig. 2 is a top view of the fixture and pole.

The fixture shown comprises a body part 5 in the form of a length of ordinary wrought iron pipe whose lower section 6 is bent into a half circle to bring the end 7 into parallelism with the main part of the body. At intermediate points of the body are side brackets 8 and 9 each formed by giving the end of a piece of ordinary pipe a quarter bend, the inner ends of the pipe being secured to the body by means of suitable castings 10 and 11, the brackets being so secured that their outer ends 8' and 9' are parallel with the body and the brackets are preferably in the same plane with the curved end 6 of the body. The ends 7, 8' and 9' are preferably tapered by forging in order to receive suitable thimbles 12 for supporting insulators such as 1. As shown, these thimbles are in the form of wire helices although other types of thimbles may be used. It is also evident that the bracket ends could be threaded to directly receive insulators, or threaded to receive the thimbles cemented into insulators.

The castings 10 and 11 are preferably so

spaced that the insulator supporting ends of the brackets and the insulators received thereby will be equidistant. In the particular arrangement shown the insulator supporting thimbles are equidistant and the brackets 6 and 9 are on one side of the body and the bracket 8 on the other with its thimble vertically mid-way between the thimbles of the brackets 6 and 9, this being a desirable arrangement for three-wire suspension. Each of the castings shown comprises a base 13 mounting a vertical sleeve 14 and a lateral flange or sleeve 15. The body 5 extends through the sleeves of the castings while the inner ends of brackets 8 and 9 extend into the lateral sleeve 15 of the lower and upper castings respectively. As shown, the body 5 is secured to the castings by pins 16. The brackets may be threaded into the lateral sleeves or may also be secured by means of pins 16. The inner faces of the bases 13 of the castings are preferably concaved to fit the surface of the pole p to which the fixture is secured, and in order to rigidly secure the fixture bolt holes 17 are provided through the castings and the body 5 has registering bolt holes for receiving bolts 18 which preferably extend entirely through the hole. Such bolts together with the concave bases of the castings will securely and rigidly hold the fixture to the pole without need of cutting gains in the pole. The fixture may of course be secured to the pole at any point. However, in high tension service work it is desirable to provide a guard wire and for this purpose I have shown the upper end 5' of the body 5 extended a distance above the upper bracket and I provide a suitable clamp 19 for securing the guard wire to the fixture. Where the fixture is thus extended for receiving a guard wire, it is preferably secured to the pole near the upper end thereof as shown, in order that the guard wire will clear the pole.

With the above construction a very strong and durable fixture is produced, the body 5 being continued through and rigidly secured to the castings to form a rigid support for the brackets 8 and 9 and the through bolts together with the rounded backs of the castings will assure rigid and secure support of the fixture on the pole. As protection against the weather it is desirable to hot galvanize the fixture both inside and outside after assembly thereof. This will

greatly prolong the life of the fixture and preserve its strength. The ends of the brackets can be fitted to receive any desired type of insulator.

- 5 I do not of course desire to be limited to the exact construction, form and arrangement shown as modifications may be possible which would still come within the scope of the invention and
- 10 I claim as follows:
1. In an insulator supporting fixture, the combination of a body part in the form of a single length of metal bent upwardly at its lower end to form an insulator supporting bracket, fittings secured to the body and spaced above the lower bent end thereof, and side brackets secured to and extending from said fittings, said fittings being adapted to be secured directly to a support to thereby support the fixture.
  2. An insulator supporting fixture comprising a straight vertical body part whose lower end is gradually bent upwardly to form an insulator supporting bracket, a side bracket secured to and extending from the body part above the lower bracket thereon, and another side bracket extending from the body part at the point between said other brackets but in the opposite direction, insulator supporting means at the ends of the brackets and said insulator supporting means being equidistantly apart.
  3. An insulator supporting fixture comprising a body part in the form of a length of pipe, the lower section of the body part being bent gradually upwardly to form a lower insulator supporting bracket, an upper and lower fitting secured to the body part, an upper side bracket extending from the upper fitting on the same side as the lower bracket, and an intermediate bracket extending from the lower fitting in a direction opposite to that in which the other brackets extend, and insulator supporting means on each bracket and said insulator supporting means being spaced equidistantly.
  4. An insulator supporting fixture comprising a body part in the form of a length of pipe bent upwardly at its lower end to form an insulator supporting bracket, a fitting receiving and secured to the body above the lower bracket, and a second bracket secured to and extending from said fitting in a direction opposite to that of the first mentioned bracket, said fittings being adapted to be secured directly to a support to thereby support the fixture.
  5. An insulator supporting fixture comprising a body part in the form of a length of pipe bent gradually upwardly at its lower end to form a lower insulator supporting bracket, upper and lower fittings receiving and secured to the body above the bracket thereon, an upper bracket secured to and extending from the upper fitting on the same

side of the body part as the lower bracket, and a bracket secured to and extending from the lower fitting in the opposite direction.

6. An insulator supporting fixture comprising a body part in the form of a length of pipe bent upwardly at its lower end to form an insulator supporting bracket, a fitting receiving and secured to the body above the lower bracket, and a second bracket secured to and extending from said fitting in a direction opposite to that of the first mentioned bracket, the back of the fitting being curved to fit the curvature of a pole to which the fixture is applied and said fitting having a bolt hole for receiving a bolt for securing the fixture to the pole.

7. An insulator supporting fixture comprising a body part in the form of a length of pipe bent gradually upwardly at its lower end to form a lower insulator supporting bracket, upper and lower fittings receiving and secured to the body above the bracket thereon, an upper bracket secured to and extending from the upper fitting on the same side of the body part as the lower bracket, and a bracket secured to and extending from the lower fitting in the opposite direction, said fittings having curved backs to fit the curvature of a pole to which the fixture is applied, and said fittings having bolt holes for receiving bolts for securing the fixtures to the poles.

8. An insulator supporting fixture comprising a vertical body part in the form of a length of pipe bent upwardly at its lower end to form an insulator supporting bracket, fittings receiving and secured to said body and having rounded backs for fitting the curvature of a pole and having also bolt holes for receiving bolts for securing them to the pole, and a lateral insulator supporting bracket secured to and extending from each fitting.

9. An insulator supporting fixture comprising a body in the form of a length of pipe bent upwardly at its lower end to form an insulator supporting bracket, fittings spaced on and receiving the body, said fittings having bolt holes and the body having registering holes through which bolts may pass to secure the fixture to a pole, and insulator supporting brackets secured to and extending from said fittings, said brackets being in a common vertical plane.

10. An insulator supporting fixture comprising a body in the form of a length of pipe bent gradually upwardly at its lower end to form a lower insulator supporting bracket, fittings receiving and secured to the body above the lower bracket, said fittings and the body received thereby having registering bolt holes through which bolts may be passed to secure the structure to a pole, and an insulator supporting bracket secured to and extending from each fitting, the end

of each bracket being adapted for the reception of an insulator and said ends being spaced equidistantly apart.

11. An insulator supporting fixture comprising a body in the form of a length of pipe bent gradually upwardly at its lower end to form a lower insulator supporting bracket, fittings receiving and secured to the body above the lower bracket, said fittings and the body received thereby having registering bolt holes through which bolts may be passed to secure the structure to a pole, and an insulator supporting bracket secured to and extending from each fitting, the end of each bracket being adapted for the reception of an insulator and said ends being spaced equidistant apart, and means at the upper end of the body for securing a guard wire thereto.

20 12. An insulator supporting fixture com-

prising a body in the form of a length of pipe bent gradually upwardly at its lower end to form an insulator supporting bracket, fittings receiving and secured to the body above the bracket thereon, said fittings and body received thereby having registering bolt holes through which bolts may pass to secure the structure to the pole, the backs of the fittings being curved to fit the curvature of the pole to which the structure is secured, and an insulator supporting bracket secured to and extending from each fitting, the ends of the brackets being adapted for the reception of insulators.

In witness whereof, I hereunto subscribe my name this 27 day of April, A. D. 1914.
